BOB PIN

Ruth K. Gaylord and Irving Richard Green, Chicago, Ill., assignors to Gaylord Products, Incorporated, a corporation of Delaware

Application October 21, 1944, Serial No. 559,677

5 Claims. (Cl. 132—50)

This invention relates to improvements in bob pins and has for an object the provision of a bob pin which may readily be applied for holding hair in place, and which is not readily displaced from its hair holding position. While all bob pins are designed having the above objects in view, it is an object of the present invention to provide a bob pin which offers greater resistance to displacement than other bob pins heretofore provided for use.

It has heretofore been the practice to design bob pins with a relatively large number of crimps in one of the legs, and then to depend upon the clamping force exerted by the legs for preventing displacement of the pin from the hair. It is obvious that bob pins of this type are faulty in design for the following reasons. When the clamping force exerted by the legs is distributed over a relatively large number of crimped surfaces, little resistance to displacement is offered by individual crimps. Further, hair receiving pockets formed by numerous crimps are so shallow that they offered little resistance to displacement of pins from the hair, and, in fact, often act to defeat the purpose for which they were provided as they tend to urge the bob pin out of engagement with the hair. In futile attempts made to improve the hair engaging action of the legs, hairpins were formed of relatively high carbon spring steel to thereby increase the clamping force exerted by the legs, and which could only result in an increased cost without improved results.

The present invention contemplates the provision of a bob pin having one leg crimped to provide relatively large hair receiving pockets having abutment shoulders arranged to prevent ready disengagement of the pin from the hair.

It is a further object of this invention to provide a hairpin of the clamping type which may be readily opened for clamping engagement with hair.

This invention embodies other novel features which are hereinafter set forth in the specification and claims and illustrated in the accompanying drawings, wherein:

Fig. 1 is a side elevational view showing a clamping type bob pin embodying features of this invention.

Fig. 2 is a top plan view of same.

Fig. 3 is a side elevational view illustrating the manner in which a clamping type bob pin may readily be opened for use.

Fig. 4 is a side elevational view showing a modified form of this invention.

Fig. 5 is a side elevational view showing another modified form of this invention.

Fig. 6 is a top plan view of same.

Fig. 7 is a side elevational view showing another modified form of this invention.

Fig. 8 is a side elevational view showing a bob pin of the type heretofore known in which relatively shallow hair engaging pockets were provided for engagement with the hair.

- 10 Referring now to the drawings and more particularly to Figs. 1 to 3 therein, a clamping type of bob pin is shown as comprising a pair of legs 8 and 9 connected by a loop 11. While the bob pin may be formed of any suitable resilient material, the design illustrated is preferably formed of resilient wire to provide resilient legs of gradually decreasing thickness and gradually increasing width, and a relatively thick non-resilient loop.
- 20 As shown in Fig. 1, the leg 9 is bent inwardly at an angle of from between 35° and 90° from the leg 8 to provide a relatively large hair receiving pocket 13 and a hair locking abutment shoulder 14. It will also be observed that the leg portion 12 and the adjacent portion of the leg 8 are substantially parallel between the loop 11 and the abutment shoulder 14, and due to the relatively short leverage and the relative non-resiliency of the loop portion 11 the hair is tightly clamped within this pocket 13 to prevent displacement of the bob pin.

- 30 A pair of relatively large capacity hair receiving pockets 16 and 17 are provided between the pocket 13 and the free ends of the legs by forming the leg 9 with relatively long outwardly divergent side portions 18 and 19, respectively, and inwardly disposed abutment shoulders 21 and 22, respectively. The abutment shoulders 21 and 22 are also disposed at an angle of from 35° to 90° from the leg 8, and the side portions 18 and 19 preferably extend approximately three to four times the length of their abutment shoulders. The inner ends of the abutment shoulders 14, 21 and 22 are preferably normally disposed in engagement with the leg 8. The free end of the leg 9 is disposed parallel to the leg 8 at 23 and may be bent outwardly therefrom at 24 if desired to provide an inwardly converging hair receiving opening. It will be observed that the leg 8 extends slightly beyond the end of the leg 9. The leg 8 may be formed either straight or arcuate as shown.

- 50 As illustrated in Fig. 3, a bob pin of the type thus described may readily be opened for use by holding the free end of the leg 8 and the loop

11 between the thumb and finger of one hand and then gripping the side portion 19 of the leg 9 between the thumb and finger of the other hand.

It has heretofore been the practice in the opening of the type of pin shown in Fig. 8 to insert a finger nail under the free end of the crimped leg, which practice is obviously objectionable due to injuries to the fingers of the user. Fig. 8 further illustrates the manner in which crimps have heretofore been formed in bob pins for the purpose of retaining same against displacement, but without attaining the desired results due to the fact that little, if any, frictional resistance is offered by the crimps to displacement of the pin. Obviously, the provision of legs offering greater resistance to opening did not solve the problem and only resulted in greater effort on the part of the user in opening the bob pin for use.

Fig. 4 shows a modified form of this invention which is similar to the form heretofore shown and described, but in which the portion 24 is turned outwardly adjacent the inner end of the abutment shoulder 22, thereby omitting the parallel portion 23 shown in Figs. 1 to 3.

Figs. 5 and 6 show another modified form of this invention in which the leg 8b is offset at 26, 27 and 28 for snug engagement against the inner ends of the abutment shoulders 14b, 21b and 22b. This form of the invention is otherwise similar to the forms heretofore described and shown in Figs. 1 to 4 in the drawings.

Fig. 7 shows another modified form of this invention in which the leg 8c is formed with recesses 31 and 32 to receive the inner ends of the abutment shoulders 14c and 21c, and which is otherwise similar to the form of this invention shown in Figs. 1 to 4.

While this invention has been shown in several forms, it is obvious to those skilled in the art that it is not so limited but is susceptible of various changes and modifications without departing from the spirit and scope of the claimed invention.

We claim as our invention:

1. A bob pin formed of round resilient wire, comprising a loop, a pair of flattened legs of gradually increasing width and gradually decreasing thickness depending from said loop, one of said legs having relatively long outwardly diverging portions and relatively short outwardly converging portions, said outwardly converging portions having their inner ends normally engaging the other leg and being disposed at an angle of from 35° to 75° from the longitudinal axis of the bob pin to serve as abutment shoulders for yieldably resisting displacement of the bob pin from the hair.

2. A bob pin formed of round resilient wire, comprising a loop, a pair of flattened legs of gradually increasing width and gradually decreasing thickness depending from said loop, one of said legs having relatively long outwardly diverging portions and relatively short outwardly converging portions, said outwardly converging portions having their inner ends normally engaging the other leg and being disposed at an angle of from 35° to 75° from the longitudinal axis of the bob

pin to serve as abutment shoulders for yieldably resisting displacement of the bob pin from the hair, said outwardly diverging portions being approximately three to four times the length of the outwardly converging portions, that portion of the crimped leg disposed between the abutment shoulder and the connecting loop being substantially parallel to the opposing portion of the other leg.

3. A bob pin formed of round resilient wire, comprising a loop, a pair of flattened legs of gradually increasing width and gradually decreasing thickness depending from said loop, one of said legs being uncrimped and the other of said legs having relatively long outwardly diverging portions and relatively short outwardly converging portions, said outwardly converging portions being disposed at an angle of from 35° to 75° from the longitudinal axis of the bob pin to serve as abutment shoulders for yieldably resisting displacement of the bob pin from the hair, said outwardly converging portions having their inner ends normally in engagement with the opposite leg and yieldably resistant to movement therewith, that portion of the crimped leg disposed between the abutment shoulder and the connecting loop being substantially parallel to the opposing portion of the other leg.

4. A bob pin formed of round resilient wire, comprising a loop, a pair of flattened legs of gradually increasing width and gradually decreasing thickness depending from said loop, one of said legs having relatively long outwardly diverging portions and relatively short outwardly converging portions, said outwardly converging portions having their inner ends normally engaging the other leg and being disposed at an angle of from 35° to 90° from the longitudinal axis of the bob pin to serve as abutment shoulders for yieldably resisting displacement of the bob pin from the hair, the other of said legs being offset adjacent the inner ends of said outwardly converging portions to provide a line engagement therewith, the remaining portion of said other leg being disposed in spaced relation to the opposing leg to provide a plurality of relatively large hair receiving pockets.

5. A bob pin formed of round resilient wire, comprising a loop, a pair of flattened legs of gradually increasing width and gradually decreasing thickness depending from said loop, one of said legs having relatively long outwardly diverging portions and relatively short outwardly converging portions, said outwardly converging portions having their inner ends normally engaging the other leg and being disposed at an angle of from 35° to 90° from the longitudinal axis of the bob pin to serve as abutment shoulders for yieldably resisting displacement of the bob pin from the hair, the other of said legs being recessed to receive the inner ends of said outwardly converging portions, the remaining portion of said other leg being disposed in spaced relation to the opposing leg to provide a plurality of relatively large hair receiving pockets.

RUTH K. GAYLORD.

IRVING RICHARD GREEN.
